UNITED STATES PATENT OFFICE.

EDWARD A. FARR, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A POT-BODY.

45,333.

Specification for Design.

Patented Mar. 3, 1914.

Application filed December 11, 1913. Serial No. 806,116. Term of patent 7 years.

To all whom it may concern:

Be it known that I, EDWARD A. FARR, a citizen of the United States, residing at Meriden, New Haven county, Connecticut, have invented a new, original, and ornamental Design for a Pot-Body, of which the following is a specification, reference being had to the accompanying drawing, forming a part thereof, in which the figure

shown is a view in side elevation of my new and ornamental design for a pot-body.

I claim:

The ornamental design for a pot body as shown.

EDWARD A. FARR.
